FISH LURE

Benjamin Amato, Galveston, Tex.

Application June 5, 1950, Serial No. 10,371

Term of patent 7 years

(Cl. D31—4)

To all whom it may concern:

Be it known that I, Benjamin Amato, a citizen of the United States, residing at Galveston, in the county of Galveston and State of Texas, have invented a new, original, and ornamental Design for a Fish Lure, of which the following is a specification, reference being had to the accompanying drawing, forming part thereof.

Figure 1 is a rear perspective view of a fish lure showing my new design;

Figure 2 is a side elevational view;

Figure 3 is a top plan view thereof; and

Figure 4 is a rear end elevational view of the same.

The essential features of the design are shown in full lines.

I claim:

The ornamental design for a fish lure, as shown and described.

BENJAMIN AMATO.
